UNITED STATES PATENT OFFICE.

JOHN E. BELL, OF BARBERTON, OHIO, ASSIGNOR TO THE BABCOCK & WILCOX COMPANY, OF NEW YORK, N. Y., A CORPORATION OF NEW JERSEY.

SUPERHEATER-BOILER.

No. 857,015.

Specification of Letters Patent.

Patented June 18, 1907.

Application filed April 4, 1905. Serial No. 253,834.

To all whom it may concern:

Be it known that I, JOHN E. BELL, of Barberton, Summit county, Ohio, have invented a new and useful Superheater-Boiler, of which the following is a full, clear, and exact description, reference being had to the accompanying drawings, forming part of this specification, in which—

Figure 1 is a diagrammatic sectional front elevation showing one form of my improved superheater boiler; Fig. 2 is a sectional side elevation of the same; Figs. 3 and 4 are views similar to Figs. 1 and 2 respectively showing a modified form; and Figs. 5 and 6 are also views similar to Figs. 1 and 2 showing another arrangement of the furnace.

My invention relates to that class of water tube boilers wherein two or more longitudinal mud drums are connected by water tubes to one or more longitudinal steam and water drums, the gases passing longitudinally of the drums and preferably being given up and down passes by baffles.

The object of the invention is to combine a superheater in the structure of said boilers in an efficient and economical manner.

In the drawings referring to the form of Figs. 1 and 2, I show one longitudinal steam and water drum 2 connected by banks of tubes 3 to two longitudinal mud drums 4, 4. 5 is the front wall, 6 the rear wall of the setting, 7 the furnace and 8 the offtake flue. 9 is the roof or arch of the combustion chamber which in this form is below the boiler, 35 the arch extending a portion of the length of the mud drums and having baffle extensions 10 which protect the mud drums, while allowing the gases to flow up through the three ports into the rear of the water tubes 3. 11 is an upwardly extending baffle between the water tubes, and 12 is a depending baffle at the front of the water tubes. In this form I show the superheater as consisting of two banks of superheating tubes 13 which connect the upper compartments 14 and 15 of the drum 2 with the compartments 16 of the two drums 4, 4. The compartments 14 and 15 are formed by a transverse partition 17 having a hole or opening near its top above the water level, and a closed partition 18. The chamber 16 in the lower drums are formed by complete partitions 19 one for each drum. 20 is the

steam outlet. In this form the gases rise through the first pass of water tubes, descend through the second pass of water tubes and then rise through the last pass among the superheating tubes, to the offtake. The steam passes from the rear part of the drum 2 into the compartment 14, flows down through the two sets of tubes into the chambers 16 and thence rises through other of the tubes 13 to the chamber 15 whence it is taken off.

In Figs. 3 and 4 I show a form similar to Figs. 1 and 2, except that three mud drums 4^a are provided, the baffles 10^a being correspondingly altered. In these figures parts similar to those of Figs. 1 and 2 are designated by similar numerals with the letter "a" applied.

In Figs. 5 and 6 I show forms similar to those of Figs. 3 and 4, except that the furnace 7^b is external and discharges directly into the lower portion of the water tubes 3^b, above the mud drums. Parts in these figures similar to those of Figs. 3 and 4 are designated by similar numerals, with the letter "b" applied.

The advantages of my invention result from the efficient and economical arrangement of the superheater in combination with a boiler of the class specified.

Many changes may be made in the form and arrangement of the furnace, the drums, the superheater connections, etc., without departing from my invention.

I claim:

1. A water tube boiler having at least two longitudinal mud drums connected by banks of tubes to an upper longitudinal steam drum or drums, means for passing gases longitudinally of the drums among the tubes, and a superheater in the boiler setting and having superheating tubes exposed to the gases the boiler having water tubes located between the source of heat and the superheater; substantially as described.

2. A water tube boiler having at least two longitudinal mud drums connected by water tubes to one or more longitudinal steam and water drums, baffles arranged to give the gases up and down passes among the tubes longitudinally of the drums, and a superheater located in the boiler setting back of the first pass, said superheater being exposed

to the heat of the gases and connected to the steam space of the boiler; substantially as described.

3. A water tube boiler having at least two longitudinal mud drums connected by water tubes to one or more longitudinal steam and water drums, baffles arranged to give the gases serial up and down passes longitudinally of the drums and among the water tubes, and a superheater forming at least the major portion of the heating surface in a pass back of the first pass of the gases among the tubes; substantially as described.

4. A water tube boiler having at least two longitudinal mud drums connected by water tubes to one or more longitudinal steam and water drums, a part of each of the drums being cut off by a transverse partition forming steam chambers, and superheating tubes connecting said chambers; substantially as described.

5. A water tube boiler having a plurality of mud drums with cross partitions forming steam chambers for a part of their length, and superheating tubes connected to said steam chambers, said boiler having water tubes between the source of heat and the superheater; substantially as described.

6. A water tube boiler having longitudinal mud drums connected by banks of tubes to one or more longitudinal steam and water drums, means for passing gases over the tubes longitudinally of the drums partitions forming steam chambers in each drum, and superheating tubes connecting said steam chambers; substantially as described.

7. A water tube boiler having at least two longitudinal mud drums connected by upright water tubes to one or more upper longitudinal steam and water drums, baffles arranged to give the gases up and down passes longitudinally of the drums among the tubes, the drums having transverse partitions dividing them into water and steam chambers,

the water chambers being located between the source of heat and the steam chambers, and upright superheating tubes connecting the upper and lower steam chambers and forming at least a major part of the heating surface in one pass of the gases in rear of the first pass, substantially as described.

8. A water tube boiler having two or more longitudinal mud drums connected by upright banks of tubes to an upper longitudinal steam and water drum, the steam and water drum having a partition dividing it into steam and water chambers, upright superheating tubes connected to the steam chambers, and means for passing the heat up and down over the tubes in the longitudinal direction of the drums; substantially as described.

9. A water tube boiler having a plurality of longitudinal mud drums connected by water tubes to a longitudinal steam and water drum, baffles arranged to give the gases up and down passes over the tubes and in the longitudinal direction of the drums, and a superheater in the boiler setting located in one of the passes in rear of the first pass; substantially as described.

10. A water tube boiler having a plurality of longitudinal mud drums connected by water tubes to a longitudinal steam and water drum, baffles arranged to give the gases up and down passes over the tubes and in the longitudinal direction of the drums, and a superheater in the boiler setting located in one of the passes in rear of the first pass, said superheater forming the major portion of the heating surface in its pass; substantially as described.

In testimony whereof I have hereunto set my hand.

JOHN E. BELL.
